UNITED STATES PATENT OFFICE.

ARTHUR J. COUGHTRY, OF LORAIN, OHIO.

PORTABLE DRILLING AND REAMING MACHINE.

1,306,467.

Specification of Letters Patent. Patented June 10, 1919.

Application filed October 30, 1918. Serial No. 260,261.

To all whom it may concern:

Be it known that I, ARTHUR J. COUGHTRY, a citizen of the United States, residing at Lorain, in the county of Lorain and State 5 of Ohio, have invented a certain new and useful Portable Drilling and Reaming Machine, of which the following is a specification.

This invention has for its object a portable machine for drilling and reaming and similar operations, and particularly applicable for drilling and reaming rivet holes in shipbuilding, which machine is particularly simple in construction and highly efficient 10 and rapid in operation, and it consists in the novel features and in the combinations and constructions hereinafter set forth and claimed.

In describing this invention, reference is had to the accompanying drawings in which like characters designate corresponding parts in all the views.

Figure 1 is a side elevation of one embodiment of my machine.

Fig. 2 is a sectional view taken on line 2—2, Fig. 1.

This machine comprises generally, a body or frame, a tool carrier mounted in the frame, a series of tools as reamers mounted 30 in the tool carrier and rotatable relatively thereto, the carrier being movable by the movement of the body over the work to carry the tools successively into operative position, and means for rotating the tools. 35 The body 1 may be of any suitable form, size and construction and as here shown includes opposite side bars which terminate at their upper ends in handles 2 and which have truck wheels 3 at their lower ends.

40 4 is a tool carrier which is here shown as rotatable and in the general form of a hollow cylinder or a disk having hub 5 and an annular flange 6. The hub 5 is mounted on a shaft 7 carried by the frame as hereinafter set forth.

45 8 are the tools as reamers mounted in the flange 6 of the carrier and extending radially outwardly relatively to the carrier 4, the reamers having spindles or shanks 9 extending through the flange 6.

The reamers are rotated about their own axes by means carried by the body or frame 1 and, as here shown, this means includes a driving gear 10 mounted concentric with the 55 carrier 4 and meshing with beveled gears 11 mounted on the inner ends of the spindles

9 and means also carried by the body 1 for actuating the gear 10.

The gear 10 is mounted on the shaft 12 arranged in alignment with the shaft 7 and 60 carried by the side bar 1 of the frame opposite the side bar supporting the shaft 7 and the shaft 12 is formed with a bearing 13 at its inner end for receiving the inner end of the shaft 7.

The means for actuating the gear 10 comprises a motor 14 carried by the body or frame between the upper ends of the side bars 1 and within a suitable annular frame element 15, a shaft 16 connected to the motor and journaled in a bracket 17 supported between the side bars 1 of the frame, a second shaft 18 also journaled in bearings formed in the bracket 17 and in a third bracket 19, intermeshing gears 20 and 21 70 mounted respectively on the shafts 16 and 18 and intermeshing gears 22, 23 mounted respectively on the lower end of the shaft 18 and on the gear 10, the gear 23 being here shown as formed integral with the gear 10. 75

The motor 14 may be an electric motor or an air motor and is connected with a suitable supply of power through electric wires or an air pipe connectible at 24 to the motor. The operation of the motor is controlled by suitable levers 25 and 26.

The carrier 4 and reamers 8 constitute a wheel which support the body or frame 1 and the side bars of the frame fulcrum on the shafts 7 and 12 and the weight of the 90 parts carried by the reamer above the shafts 7 and 12 is counterbalanced or partly counterbalanced by a weight 27 located at the lower ends of the arms of the side bars 1 between the truck wheels 3.

In operation, the holes having been previously drilled in a horizontal surface or the location of the holes to be drilled indicated or marked off, the machine is then moved on the truck wheels 3 by lifting on the handles 100 2 to place one of the tools 8 in one hole or on the center mark indicating the position of the hole to be drilled. The motor is then started so that the reamers are rotated through the shaft 16, gears 20, 21, shaft 18, 105 gears 22, 23, driving gear 10 and beveled gears 11, the body being tilted about the axis of the carrier 4, that is, about the shafts 7 and 12 to lift the truck wheels off the surface so that the weight of the machine is applied to the drill or reamer in operative position. The operator then pushes or wheels 110

the machine over the work, (the machine being supported by the carrier and one of the tools) to bring a new tool into position to ream or drill another hole and to lift the first 5 tool out of operative position.

This operation is repeated along a line or series of holes, the operator merely wheeling the machine along on the wheel constituted by the carrier 4 and the tools 8.

10 The carrier 4 is removable and interchangeable with other carriers having differently spaced tools, it being understood that the tools are spaced so as to properly space the holes to be reamed or bored in the 15 work.

This machine is particularly advantageous especially in shipbuilding as a large number of all the rivet holes can be reamed in a short time compared with the method 20 now used.

What I claim is:

1. A portable drilling and reaming machine comprising a movable body, a movable tool carrier mounted on the body and a 25 series of tools mounted on the carrier, the carrier being movable by the advance movement of the body to bring the tools successively into operative position, and means for actuating the tools, substantially as and for 30 the purpose described.

2. A portable drilling and reaming machine comprising a movable body, a rotatable tool carrier mounted in the body, a series of tools mounted in the carrier and arranged to 35 come successively into operative position during rotation of the carrier, and means for rotating the tools, substantially as and for the purpose specified.

3. A portable drilling and reaming machine comprising a movable body, a movable tool carrier mounted in the body, a series of rotatable tools mounted in the carrier, the tool carrier being movable by the advance movement of the body to carry the 45 tools successively into operative position, and means for actuating the tools comprising a driving gear and gears associated with the respective tools and meshing with the driving gear, substantially as and for the purpose 50 set forth.

4. A portable drilling and reaming machine comprising a body, a rotatable tool carrier mounted in the body, rotatable tools extending radially outwardly relatively to 55 the carrier, the carrier and tools constituting a wheel rotatable during the movement of the body over the work, and means for rotating the tools, substantially as and for the purpose described.

60 5. A portable drilling and reaming machine comprising a body, a rotatable tool carrier mounted in the body, rotatable tools extending radially outwardly relatively to the carrier, the carrier and tools constituting a 65 wheel supporting the body and rotatable

during the movement of the body over the work, and means for rotating the tools, substantially as and for the purpose specified.

6. A portable drilling and reaming machine comprising a body, a rotatable tool carrier mounted in the body, tools extending radially relatively to the carrier, the carrier and rotatable tools constituting a wheel supporting the body and rotatable during the movement of the body over the work, and 70 means for rotating the tools, said means comprising a driving gear arranged concentric with the carrier, and gears movable with the carrier and meshing with the driving gear, substantially as and for the purpose set 75 forth.

7. A portable drilling and reaming machine comprising a movable body, a tool carrier mounted in the body, a series of tools supported by the carrier and movable successively thereby into operative position, the tool carrier and tools supporting the body, the carrier being movable to carry the tools successively into operative position during 80 the movement of the body, and means carried by the body for actuating the tools, substantially as and for the purpose described.

8. A portable drilling and reaming machine comprising a body, a rotatable tool carrier mounted in the body, rotatable tools 95 extending radially outwardly relatively to the carrier, the carrier and tools constituting a wheel supporting the body, and rotatable by the movement of the body over the work, and means carried by the body and connected to the tools for rotating the same, substantially as and for the purpose specified.

9. A portable drilling and reaming machine comprising a body, a rotatable tool carrier mounted in the body, tools extending radially relatively to the carrier, the carrier and tools constituting a wheel supporting the body and rotatable during the movement of the body over the work, and means for rotating the tools, said means comprising a driving gear arranged concentric with the carrier, and gears arranged in annular series and connected to the tools and engaging the driving gear, and means carried by the body for actuating the driving gear, substantially as and for the purpose set forth.

10. A portable drilling and reaming machine comprising a body, a tool carrier rotatably mounted in the body and having a 120 series of tools on its periphery arranged to be brought successively into operative position, the body being fulcrumed on the axis of the tool carrier and extending in front and in the rear of said axis, and means carried by the body for rotating the tools, substantially as and for the purpose described.

11. A portable drilling and reaming machine comprising a body, a tool carrier rotatably mounted in the body and having a 125

series of tools on its periphery arranged to be brought successively into operative position, the body being fulcrumed on the axis of the tool carrier and extending in front 5 and in the rear of said axis, and means carried by the body for rotating the body and the tools, the parts carried by the body be-

ing balanced on the axis of the carrier, substantially as and for the purpose specified.

In testimony whereof, I have hereunto 10 signed my name, at Lorain, in the county of Lorain, and State of Ohio, this 15th day of October, 1918.

ARTHUR J. COUGHTRY.
